UNITED STATES PATENT OFFICE.

ROBERT M. MCFADDEN, OF HAVANA, ILLINOIS.

ELECTRIC WELL-BORING TOOL.

1,419,068.

Specification of Letters Patent. Patented June 6, 1922.

Application filed February 5, 1920. Serial No. 356,441.

To all whom it may concern:

Be it known that I, ROBERT M. MCFADDEN, a citizen of the United States, residing at Havana, in the county of Mason and State 5 of Illinois, have invented new and useful improvements in Electric Well-Boring Tools, of which the following is a specification.

This invention relates to well drilling apparatus and has for its object to provide improvements in well drilling tools of the rotary type and by which improvements the power plant for driving the tools is self-contained in a unit adapted to be lowered into the well hole and follow directly the cutting 15 tool for the purpose of eliminating expensive, heavy, and unwieldy driving parts handled with difficulty as the depth of the drilling proceeds, and the invention consists of the construction, the combination and 20 details and arrangements of parts an embodiment of which is illustrated in the accompanying drawings and described and claimed herein.

Figure 1 is a vertical transverse sectional view of the motor and locking parts at the upper part of the unit.

Fig. 1^A is a vertical section taken centrally through the lower part of the unit.

Fig. 2 is a transverse vertical longitudinal 30 view partly in elevation of the underreamer.

Fig. 3 is a transverse horizontal section on line 3—3 of Fig. 1^A.

Fig. 4 is a transverse horizontal section on line 4—4 of Fig. 2.

Fig. 5 is a vertical section through a portion of the underreamer body showing a retained underreaming cutter.

Fig. 6 is a transverse section on line 6—6 of Fig. 1.

Fig. 7 is a side elevation of the spider structure at the head of the unit being at right angles to the plane of Fig. 1.

Fig. 8 is a transverse section on line 8—8 of Fig. 1.

One of the principal features of the present invention resides in the compact organization forming a combined unit with a self-contained power plant and drilling or cutting means, and in the illustrated embodiment of the invention the unit comprises a casing having a head or cap member 2 internally threaded as at 3 to be threaded upon the upper end of a longitudinally split shell

or body 4 with edges shown in elevational view in Fig. 1. The assembled halves of the 55 split shell 4 may be locked against unthreading by suitable means such as screws 5.

The shell or body 4 of the upper portion of the casing may be of any suitable length, and in Fig. 1^A the halves of the shell 4 are 60 shown as connected against separating by a lock ring 6 having an inner sleeve or bushing-like part 7 fitting the complementary bore of the lower end of the casing part 4, the ring having also an exterior sleeve part 65 8 internally threaded to take exterior threads 9 formed on the lower ends of the halves forming the split shell 4. The ring 6 also forms a renewable race or track for internally arranged roller bearings 10 a suitable 70 number of which may be provided on the upper end of the reamer casing or body 11, the upper end of this body being turned down and of sufficient size to extend upwardly into the sleeve 7 and which upwardly extending portion is internally threaded as at 12 to be threaded on to the reduced and externally threaded lower end 13 of an inner gear box or casing 14 which preferably also is longitudinally split for the purpose of 80 convenient arrangement of the interior parts.

The antifriction rollers 10 are provided at their ends with trunnion pins or stud shafts 10' which respectively extend into bearings provided in one instance, in the upper end of the reamer casing, as clearly shown in Fig. 1^A, while the other end pins 10' of the rollers are mounted in rings 10^a clamped about the upper reduced end of the casing when the latter is screwed into place 90 on the reduced part 13 above described.

The parts of the inner gear box or casing 14 may be connected by suitable transverse bolts 15 which extend through an inwardly turned flange or head 16 on opposite sides 95 of which are provided upper and lower sets of ball or other antifriction bearings as 17 and 18 respectively; these bearings being adapted to take end thrust of the operating mechanism to be described hereinafter.

The lower set of bearings 18 run on a diametrical cheek-plate or disc 19 having a hub 20 which is conically threaded as at 21 to take the complementary threaded cone or hub 22 that is mounted in fixed position 105 inside of the exterior and upper casing 4.

Such connection may be obtained by means of a flange 23 extending diametrically from the upper end of the hub 22, and into the flange there may be threaded fastening 5 screws or other suitable means 24 passed through apertures 25 provided therefor in the casing 4 just above an inwardly extending diametrical web 26 fitting an annular space formed between the upper flange 23 10 and a lower flange 23' which forms a bearing against the thrust of the upper set of anti-friction bearings 17.

From the above it will be seen that there is provided an exterior jacket or casing including the cap 2 serving to secure the lower longitudinally split casing body 4 which is of suitable length and has its lower end secured in assembled organization by the lock ring 6. In the upper end of the casing 4 15 there is provided a motor plant, in the present instance, comprising a plurality of armatures 27 any suitable number of which may be employed to provide the necessary power for driving the drilling tools, these armatures rotating in respective fields 28 within the upper end of the casing 4, and the armatures are secured on a shaft 29 the upper end of which runs on end thrust bearings 30 having a race mounted on a bridge 31 or spider extending diametrically or otherwise arranged across the upper end of the casing 4, and below this spider or bearing part there is provided an oiling cup or device 32. The motor organization is contained internally within the upper casing parts and does not extend through the cap 2.

The motor shaft 29 is provided immediately below the lower armature 27 with a suitable bearing 33 that is supported on a 40 central bearing part 34 formed on or attached to the casing 4, and at any suitable location in the casing there may be provided an oiling device or means for facilitating the introduction of oil as for instance an oil 45 plug 35, Fig. 1.

The motor shaft passing through the bearing 34 extends downwardly through the bearing or central hub 22 above described as held stationary, and on this shaft below 50 the end of the bearing 22 there is provided a pinion 36 engaging and driving a reducing gear of suitable construction. This gear may comprise one or more intermediate pinions 37 on a respective shaft or shafts 38. 55 The intermediate shaft 38 carries a gear 39 and this meshes with and drives a larger gear 40 secured or formed on a reducing shaft 41 whose lower end is mounted in a bearing plate 42 or other suitable device, in 60 this case bolted or otherwise connected as at 43 in spaced relation below the upper plate 19. These plates may be definitely spaced by suitable spacing members 44. The intermediate shaft or shafts 41 is or are provided

with a pinion or pinions 45 engaging an internal gear 46 formed on or secured to the inner face of the gear box or chamber 14 so that the latter is rotated with respect to the outer casing 4 when the latter is held stationary as will be described hereinafter.

The motor shaft 29 is shown as extending downwardly and provided with a suitable flexible joint 29' and has an extension 29" on which may be mounted a centrifugal disc or oil distributor 47 shown as arranged below the flexible joint 46, and the lower end of the shaft section 29' is mounted in a suitable bearing 48 that is formed or mounted on the interior of the lower reamer casing.

On the lower portion of the shaft section 29' there is secured a gear 49 engaging with and driving a plurality of pinions 50 that are secured on respective shafts 51 having their upper ends supported in a bearing part 52, in this case, in the form of an internal 85 annular shoulder at the upper portion of the casing 11 and which shoulder or bearing is just below the plane of the oil distributing disc 47 so that oil thrown from the latter may flow through oil holes 53 leading to the 90 journals of the upper ends of the shafts 51. The lower ends of these shafts, which shafts are shown as converging downwardly, are mounted in bearings 54 in the lower inclosed end of the underreamer casing and the extending ends of the shafts 51 are provided with removable cutters 55 of any suitable character so that these cutters are positively driven through means of the driving shaft 29-29' independently of the rotary movement of the driven under-reamer casing 11 but by which rotary movement of the latter the leading or end cutters 55 are carried in a circular orbit during which time they rotate on their own axes.

To facilitate the lowering of this drilling unit into the well being drilled and for removing the same and for locking the motor casing 4 against rotation, suitable means may be provided a form of which comprises 110 means carried by the cap or head 2 which is shown as having a set of upwardly extending legs 60 converging in a central hub 61 to which is connected a shackle 62 attached to which is a lowering and lifting cable 63. 115 The hub 61 is hollow and through it passes a tripping cable 65 on the lower end of which is mounted a collar 66, the lower end of the cable being provided with any suitable shoulder 67 to hold the collar in place against 120 slipping down.

This collar is provided with a plurality of pivot pins 68 on each of which is arranged an expanding link 69, these links being connected at their outer and swinging ends by 125 bolts or pivot members 70 which pass through respective dogs 71. The inner ends of these dogs are pivoted on pivot pins 72 passing

through suitable bearings 73 preferably of considerable length and formed in pairs spaced to receive and hold the inner ends of the dogs 71 rigidly when they have been expanded outwardly to become embedded in the wall of the well hole, as shown in Fig. 1. Normally the dogs 71, which preferably have outer weighted ends, will swing down freely in their bearings 73 while the tripping or setting cable 65 hangs slack during the lowering of the unit by the main cable 63. As the drilling proceeds the cable 63 is slackened off and the dogs 71 thrown outwardly into engagement with the surface of the well by pulling up on the setting cable 65 which causes the expansion of the links 69 by the upward movement of their carrier 66.

Electric energy is supplied to the motor in the casing 4 through an electric feed cable 74. In addition to the end cutters 55 mounted on the rotary casing section 11 the latter may also be provided with other cutting means such for instance shown in Figs. 2, 4 and 5 in which cutters in the form of blocks 75 are arranged in pockets 76 provided at suitable locations in the lower section casing 11, and the cutting blocks or tools are pivoted on pins or other suitable supports 77 extending transversely across the pockets 76, the cutters 75 preferably being overbalanced at their inner ends so that they will swing to a horizontal position as shown in Fig. 2 with their outer and operative ends exposed beyond the surface of the casing section 11 and at which time the outer portion of the upper edge of each cutter is designed to rest against an overhanging stop portion or shoulder 78 at the mouth of the pocket 76.

When the tool is first lowered into the well these several cutters 75 which are disposed substantially radially with respect to the casing section 11 are disengageably latched in contracted position, as shown in Fig. 5, by a suitable finger 80 that is turnable from the upright position on a pivot or screw 81 countersunk in the face of the casing 11 at the lower end of the mouth of the pocket 76.

As the tool is lowered into the hole being drilled and the section 11 is rotated by the motor, the fingers 80 are tripped or tilted about their pivots 81 by the friction of engagement with the walls of the hole and this automatically releases the lower ends of the cutters 75 which then automatically swing into effective cutting position.

Various changes may be made without departing from the spirit of my invention as claimed.

I claim:

1. A well drilling unit comprising a relatively stationary cylindrical housing, an electric motor arranged for operation within said housing, a drilling head rotatably connected to the housing and motor, a plurality of rotary cutting tools carried by the drilling head and driven from the motor, which unit is adapted to be bodily lowered into and removed from a well.

2. A well drilling unit comprising a cylindrical housing, an electric motor arranged for operation within said housing, a drilling head rotatably connected to the housing and motor, a plurality of rotary cutting tools carried by the drilling head and driven from the motor, which unit is adapted to be bodily lowered into and removed from a well.

2. A well drilling unit comprising a cylindrical housing, an electric motor arranged for operation within said housing, a drilling head rotatably connected to the housing and motor, a plurality of rotary cutting tools carried by the drilling head and driven from the motor, which unit is adapted to be bodily lowered into and removed from a well, means arranged on the housing for engaging the ground adjacent to said housing to retain the latter against rotation, and means for retracting said holding means in order to permit the unit to be removed from the well.

3. In a well boring unit, a substantially cylindrical body, an electric motor arranged for operation in the upper portion of said body, a revoluble head arranged for operation in the lower portion of said body, reduction driving gear connections between the motor and said revoluble head, a plurality of rotary cutting tools arranged for operation in the head and driven from the electric motor, and means on the upper portion of the cylindrical body for engaging the earth in which the device is operating to hold the main body portion thereof against rotation.

4. A well drilling unit comprising, in combination, a power plant contained within a casing; means connected to the casing for raising and lowering the same; means adapted to engage the earth to lock the casing against rotation in a well hole during the drilling thereof; means for disengaging said locking means from the earth in order to permit the unit to be withdrawn from the well; and cutting means connected to and rotatively driven by the said plant.

5. A unit set for well drilling comprising an upper casing section embodying a power plant; means adapted to engage the earth for locking the casing against rotation in a well hole; means for disengaging said locking means from the earth in order to permit the unit to be withdrawn from the well; a head casing connected on the lower end of the upper casing; said lower casing having cutting means; and means connecting the lower casing and the power plant whereby the latter is driven directly from the plant.

6. A unit set for well drilling comprising an upper casing section embodying a power plant; means adapted to engage the earth for locking the casing against rotation in a well hole; means for disengaging said locking means from the earth in order to permit the unit to be withdrawn from the well; a head casing connected on the lower end of the upper casing; said lower casing having cutting means; means connecting the lower casing and the power plant whereby the latter is driven directly from the plant.

ter is driven directly from the plant; and rotary cutters mounted on the lower casing and individually driven independently of their carrying casing.

5 7. In a rotary well drill, a casing having a motor section and a motor therein; means carried by the motor containing section of the casing for engaging the earth to lock said section against rotation; and an end section rotatively attached thereto and geared to the motor; said end section having cutter shafts geared to the motor.

10 8. In a rotary well drill, a casing having a motor section and a motor therein; means carried by the motor containing section of the casing for engaging the earth to lock said section against rotation; and an end section rotatively attached thereto and geared to the motor to be driven thereby at reduced speed; said end section having cutter shafts geared to the motor.

15 9. In a rotary well drill, a casing having a motor section and a motor therein; means carried by the motor containing section of the casing for engaging the earth to lock said section against rotation; and an end section rotatively attached thereto and geared to the motor; said end section having

cutter shafts geared to the motor and driven at an accelerated speed over the end casing.

30 10. A rotary drill apparatus comprising upper and lower aligned casing sections having swivel connections so that one may rotate as to the other, the relatively stationary section having an inclosed power plant, the other section having cutting means and means carried by the non-rotating section for engaging the earth to retain the main body portion of the apparatus against rotation.

35 11. A rotary drill apparatus comprising upper and lower aligned casing sections having swivel connections so that one may rotate as to the other, the relatively stationary section having an inclosed power plant, the other section having cutting means, said means including rotary cutters driven independently of the lower casing by the power plant and means carried by the non-rotating section for engaging the earth adjacent to which the apparatus is operated for retaining the main body portion of said apparatus against rotation.

40 In testimony whereof I have signed my name to this specification.

ROBERT M. McFADDEN.
